UNITED STATES PATENT OFFICE.

ANTHONY V. ROMADKA, OF WAUWATOSA, WISCONSIN.

TRUNK-FASTENER.

SPECIFICATION forming part of Letters Patent No. 282,780, dated August 7, 1883.

Application filed May 23, 1883. (No model.)

To all whom it may concern:

Be it known that I, ANTHONY V. ROMADKA, of Wauwatosa, in the county of Milwaukee, and in the State of Wisconsin, have invented 5 certain new and useful Improvements in Trunk Bolts and Catches Combined; and I do hereby declare that the following is a full, clear, and exact description thereof.

My invention relates to devices for securing 10 the tops of trunks to trunk-bodies when the former are closed, in place of straps and buckles secured to the front of the top and body; and it consists in certain peculiarities of construction, as will be more fully set forth hereinafter, and pointed out in the claim.

In the drawings, Figure 1 is an inside view 20 of my device in the locked position. Fig. 2 is a vertical longitudinal section thereof on the line $x-x$ of Fig. 1. Fig. 3 is an inside view 25 of the device in the unlocked position, and Fig. 4 is an outside view of the device locked.

My entire device is made of five castings, and is operated wholly without springs of any 30 description.

A is the upper plate, cast with the perforated lugs $a-a$ to adapt it to be secured to the top 35 of the trunk, and having the catch A' a' (which is L-shaped in cross-section, as shown in Fig. 2) projecting downward from the under side of its bottom flange. B is the lower 40 plate, cast with perforated lugs or flanges $b-b$, for attachment to the front of the trunk-body just under the plate A; and both these plates A and B are cast with exterior inward-projecting flanges, that of the lower plate being 45 cut away at b' on top to receive the catch A' of the upper plate, and at b^2 at the lower part of one side to afford room for the operation of the handle C' of the lever C, whose inner end 50 is formed into a segment-head provided with the cogs c , and which is mounted on a pivot, b^5 , projecting from the plate B. This plate has also cast thereon a guide, b^4 , and another guide, B^3 , from the center of which rises another pivot, b^3 , in vertical line with the pivot b^5 .

D is the locking-plate, and this is provided 55 with the central longitudinal slot, d^2 , which receives and moves upon the guide B^3 , while its lower edge is formed into a rack-bar, with cogs or teeth d adapted to mesh with the teeth e on the segment-head of the lever C, and from

one end there rises an inwardly-projecting flange, d' , terminating in the bolt D' , adapted to rest above the lip a' of the catch A' when 55 the device is in the locked position. The function of the guide b^4 is to prevent the adjacent end of the locking-plate D from dropping down should the guide B^3 become somewhat worn by use, and thus it follows that the 60 plate D will always move back and forth in a horizontal line in locking and unlocking my device.

In putting my device together in the manufacture thereof, the plate D is placed upon the 65 guide B^3 , and the lever C is placed upon the pivot b^5 with the cogs on the parts D and C in mesh, and then the covering-plate B^2 is applied above them. This plate has two holes which receive the pivots b^3 and b^5 , the ends of 70 which pivots are next upset upon the said covering-plate, whose outer edge rises to a level with the lower lugs, b , and fills in the space where the plate B was cut away at b^2 , thus permitting the handle C' of the lever C to move 75 freely between the outer wall of the plate B and the covering-plate B^2 . After this the plates A and B may be screwed or otherwise fastened to the front of the top and body of the trunk, respectively, preferably one at each 80 side of the central trunk-lock, in place of the old-fashioned straps and buckles.

The operation of my device will be apparent from the foregoing description of its construction. By simply moving the handle C' 85 of the lever C down, the catches will be instantly locked by the engagement of the parts A' and D', or, vice versa, by moving the said handle up, the said parts will be at once released from engagement and the catches un- 90 locked.

It is obvious that it is immaterial whether my lever projects from the right or left hand side of the plate B, and consequently immaterial whether the catch and bolt respectively 95 project in the positions shown, or exactly the reverse position, so long as the relative arrangement of all the parts is preserved; and it is also immaterial whether the locking is accomplished by the downward movement of the lever and the unlocking by an upward movement, or vice versa. Again, the device would work equally well if the relative positions of the two plates were reversed, so as to have the 100

bolt on the upper plate and the catch projecting from the lower plate, and the details of construction may be mechanically varied within the limits of my claim without departing from the spirit of my invention.

Having thus described my invention, what I claim as new, and desire to secure by Letters Patent, is—

A trunk-fastening consisting of two plates, one provided with a stationary or rigid projecting catch and the other provided with a bolt forming part of a slotted sliding plate

moving upon a guide, and provided with teeth or projections, in combination with a toothed lever adapted to mesh with the teeth on the bolt-plate and lock or unlock the catch by positive action independently of keys or springs.

In testimony that I claim the foregoing I have hereunto set my hand on this 11th day of May, 1883, in the presence of two witnesses.

ANTHONY V. ROMADKA.
